UNITED STATES PATENT OFFICE.

DANIEL A. WEDMORE, OF CAMDEN, NEW JERSEY.

TYING AND SUPPORTING DEVICE FOR REINFORCING WIRES OF CONCRETE STRUCTURES.

1,099,679.

Specification of Letters Patent. Patented June 9, 1914.

Application filed October 22, 1913. Serial No. 796,620.

To all whom it may concern:

Be it known that I, DANIEL A. WEDMORE, a citizen of the United States, residing in Camden, New Jersey, have invented certain 5 Improvements in Tying and Supporting Devices for Reinforcing-Wires of Concrete Structures, of which the following is a specification.

My invention consists of a tying and supporting device intended for application to the crossed reinforcing rods or bars usually embedded in concrete floors or the like for strengthening the same, the object of my invention being to provide a simple, cheap and 15 effective device which will retain the crossed bars in their proper relation to one another and also in their proper position in the form during the pouring or ramming of the concrete into the latter. This object I attain 20 in the manner hereinafter set forth, reference being had to the accompanying drawing, in which—

Figure 1 is a perspective view illustrating one form of my improved tie and support 25 as applied to a pair of crossed reinforcing bars; Fig. 2 is a side elevation of the same; Fig. 3 is a view similar to Fig. 1 but illustrating another form of my improved tie and support, and Fig. 4 is a side elevation 30 of the structure shown in Fig. 3.

In the drawing, 1 and 2 represent two of the bars of the metallic frame or network usually inserted in a mass of concrete such 35 as a floor or the like for strengthening purposes, the bars being of any desired dimensions and cross sectional form and being usually disposed at a right angle to one another and one above the other.

For convenience, I will refer to the bar 40 1 as a longitudinal bar and to the bar 2 as a transverse bar.

In order that the bars may, during the pouring or ramming of the concrete into the form in which it is molded, be retained 45 in proper relation to one another at each crossing point and also supported in proper position in respect to the mold, I employ a combined tie and support which in the form shown in Fig. 1 comprises a piece of wire 50 bent at a point some distance from the center so as to constitute a structure presenting throughout the greater portion of its length a double run, one run projecting some distance beyond the end of the other as shown at 3

in Fig. 1. The structure presents loops 4 55 and 5, a depending supporting leg 6 and parallel side members 7 and 8, the end of one run of the wire being bent lengthwise to form a hook 9 and the end of the other run being bent sidewise to form a hook 10. 60

In applying the structure to the crossed bars 1 and 2 the loop 4 embraces the under side of the longitudinal bar 1 at one side of the transverse bar 2, the loop 5 embraces the top of said transverse bar 2 on one side 65 of the bar 1, and the hook 9 engages the top of said bar 2 on the other side of said bar 1, the supporting leg 6 depending from the loop 5 in front of the bar 2 and the member 3 extending forwardly of the bar 2 at 70 one side of the bar 1 and having its lateral hook 10 engaged with the under side of said bar 1 at such forward point. The members 7 and 8 are located on opposite sides of the bar 1, the member 7 connecting the 75 loops 4 and 5 and the member 8 connecting the loop 4 to the hook 9 and member 3.

In that form of my improved supporting tie shown in Fig. 3 the structure presents a double run of wire throughout, one run 80 terminating in a right hand hook 9^a and the other in a left hand hook 10^a, both of which hooks engage the under side of the bar 1 in advance of the bar 2 but the structure being otherwise the same as that shown 85 in Fig. 1.

The structure not only serves to hold one bar firmly against the other, but also, by reason of its frictional hold upon the bars, to prevent one bar from sliding over the 90 other and the contact of the bottom of the leg 6 with the bottom *a* of the form in which the mass of concrete is to be molded serves to support the bars at the proper height above said mold bottom and thus insures the 95 desired depth of concrete below the reinforcing structure embedded in the mass of concrete.

The supporting leg 6 is inclined rearwardly from the top bar 2, as shown in 100 Figs. 3 and 4, consequently the greater the weight of the reinforcing structure the more firmly is the tie bound thereto since any weight upon the supporting leg 6 tends to swing the same in the direction of the arrow *m* Fig. 2 and thus press the loop 4 firmly into contact with the under side of the bar 1.

In order to stiffen the loop 4 I find it advisable to cross the inner and outer runs of the wire in forming the loop so that the wire which constitutes the inner run in the side member 7 constitutes the outer run in the side member 8, and vice-versa.

A tie support such as that which I have shown and described is extremely cheap, costing but the fraction of a cent, and it can be quickly applied, being first adjusted to the bars in the position shown by dotted lines in Fig. 2 and then turned in the direction of the arrow n until the hook 10 or the hooks 9^a and 10^a are in position to be engaged with the bar 1.

I claim:

1. A supporting tie for crossed reinforcing bars for concrete structures, said tie having a longitudinal loop to pass over the top of a transverse bar, a lateral loop to extend under a longitudinal bar, and side members to be disposed on opposite sides of said longitudinal bar, one side member connecting the longitudinal and lateral loops before referred to and the other adapted to extend over the top of the transverse bar and to engage the longitudinal bar, and the first named longitudinal loop having a downward extension forming a supporting leg.
2. A supporting tie for crossed reinforcing bars for concrete structures, said tie having a longitudinal loop to pass over the top of a transverse bar, a lateral loop to extend under a longitudinal bar, and side members to be disposed on opposite sides of said longitudinal bar, one side member connecting the longitudinal and lateral loops before referred to and the other adapted to extend over the top of the transverse bar and to engage the longitudinal bar, and the first named longitudinal loop having a de-

pending leg which extends downwardly and rearwardly therefrom.

3. A supporting tie for crossed reinforcing bars for concrete structures, said tie having a leg to be disposed in front of the transverse bar and depend below the bars, a longitudinal loop to pass over the top of said transverse bar, a lateral loop to extend under the longitudinal bar, and side members to be disposed on opposite sides of said longitudinal bar, one side member connecting the longitudinal and lateral loops before referred to and the other adapted to extend over the top of the transverse bar and terminating in bar-engaging hooks, said structure being composed of a doubled wire, the runs of which are reversely disposed in the opposite side members of the tie.

4. A supporting tie for crossed reinforcing bars for concrete structures, said tie having a leg to be disposed in front of the transverse bar and to depend below the bars, a longitudinal loop to pass over the top of said transverse bar, a lateral loop to extend under the longitudinal bar, and side members to be disposed on opposite sides of said longitudinal bar, one side member connecting the longitudinal and lateral loops before referred to and the other extending over the top of the transverse bar and terminating in bar-engaging hooks, one of which is bent longitudinally to engage the transverse bar and the other being bent transversely to engage the longitudinal bar.

In testimony whereof, I have signed my name to this specification, in the presence of two subscribing witnesses.

DANIEL A. WEDMORE.
